RAIL ANCHOR

Charles G. Ericson, Toronto, Ontario, Canada

Application June 14, 1932, Serial No. 617,123

6 Claims. (Cl. 238—324)

This invention relates to rail anchors for preventing rail creepage, and more particularly to a two piece type of rail anchor having a construction for maintaining a strong spring gripping action between the parts when in their working position.

It is well known to those familiar with track problems that the rails for supporting the wheels of a train tend to creep in the direction of the traffic, and that this creeping tendency has been greatly increased by the modern tendency of increasing the weight and speed of the rolling stock.

To meet these changed conditions the rail anchor of today should be capable of resisting a greater creeping force imparted to the rails by the heavier and faster moving rolling stock, and therefore should possess increased strength and rail gripping properties. It is also important that the rail anchor shall be cheap to construct both as to labor and material, and easy to apply to and remove from a rail without requiring the use of special track equipment.

The present invention relates to a two piece rail anchor, comprising a shoe and yoke of the general type disclosed in my Patent No. 1,548,589, dated August 4, 1925, but contemplates pronounced improvements over the construction of said patent, in that in the rail anchor of the patent both the shoe and yoke are given a rigid non-yielding construction so that there is an absence of a distinct spring action between the cooperating parts, whereas in the present construction the cooperating parts are designed so as to provide a distinct spring gripping action between the parts when in their working position.

In order to secure the spring gripping action contemplated by the present invention it is necessary to so construct the shoe and yoke that they will possess sufficient strength to hold the rail against the strong creeping forces that may be exerted thereupon and at the same time are sufficiently resilient to provide the desired spring action.

One important feature of the present invention resides in a resilient yoke adapted to extend across the lower face of a rail base and constructed to engage only the central lower face of the base with a fulcrum action that holds the remaining underlying portions of the yoke in yielding spaced relation to the rail base. As a result of this construction the yoke is given a spring action at each side of the central longitudinal axis of the rail that helps to hold the

upwardly extending end portions of the yoke in strong gripping action with the parts they engage. This spring action it should be noted is secured without in any way reducing the strength of the yoke to resist the creeping tendency of the rail.

Another important feature of the present invention resides in the construction of the overhanging jaw whereby this jaw exerts a strong spring gripping action upon the shoe. This is secured by imparting a longitudinal twist to the shoe engaging jaw or by beveling its lower face so that the pressure of this face upon the shoe subjects the jaw to a longitudinal torsional twist. The forming of this lower face of the jaw at an inclination to the upper face of the shoe has a further advantage in that it facilitates the insertion of the shoe in the hook portion of the yoke, and the torsional twist imparted to this overhanging jaw it should be noted gives the desired spring action without reducing the strength of the yoke.

Another important feature of the present invention resides in the construction of the shoe so that the cooperating jaws thereof provided to engage the upper and lower faces of the rail base will grip the rail base with a strong spring clamping force that prevents the shoe from sliding lengthwise of the rail when the parts are in their working relation. A further feature resides in the arrangement of these jaws so that they are spaced further apart at one end of the shoe than the other to facilitate the engagement of one end portion of the shoe with the rail base by hand. Still another feature of the invention resides in the arrangement of one longitudinally extending jaw of the shoe so that its inclination varies slightly longitudinally of the shoe and tends to cant the shoe slightly to increase the gripping action of the other jaws upon the rail base.

As a result of the spring gripping action of both the shoe and yoke the rail anchor parts will compensate for the usual inequalities and allowable tolerance in the rail base dimensions, and also compensate for slight variations which may occur in constructing the rail anchor parts so that it is unnecessary to machine any part of either the yoke or shoe. The rail anchor also combines the important qualifications of flexibility and ruggedness and is so designed that metal is omitted where not required for strength to thereby avoid waste of material and unnecessary weight.

The various features of the present invention

and novel combination of parts will be hereinafter described in connection with the accompanying drawings which illustrate one good practical form thereof.

5 In the drawings:

Fig. 1 is a perspective view of the rail anchor of the present invention in service position upon the rail;

10 Fig. 2 is a vertical section view through the rail and shoe of Fig. 1 showing the yoke in side view;

Fig. 3 is a perspective view of the shoe;

15 Fig. 4 is a top plan view of a portion of the rail showing the shoe in the preliminary position upon the rail base in which it may be applied by hand;

Fig. 5 is a top plan view of the shoe and yoke in service position upon the rail;

20 Fig. 6 is a side elevation of the shoe looking toward the jaws for engaging the rail base;

Fig. 7 is an end view of Fig. 6 looking towards the smaller end of the shoe;

25 Fig. 8 is an end view of Fig. 6 looking towards the tie engaging face of the abutment member;

Fig. 9 is a top plan view of the yoke showing the twisted shoe engaging jaw;

30 Fig. 10 is a sectional view taken on the line 10—10 of Fig. 9;

Fig. 11 is a view similar to Fig. 6 but shows 35 the yoke in engagement with the tapered end of the shoe;

Fig. 12 is a sectional view taken on the line 12—12 of Fig. 5; and

Fig. 13 is a sectional view taken on the line 35 13—13 of Fig. 4.

The rail anchor is shown as applied to a rail of the conventional type, having the usual head portion 1, intermediate web 2 and base 3. The rail base has the bottom or lower face 4, vertical 40 side edges 5 and upper sloping faces 6, and the rail is shown as resting upon the usual tie 7.

The rail anchor shown comprises a shoe constructed to fit upon an edge portion of the rail base, and a yoke adapted to span the rail base 45 and embrace the shoe and one edge of the rail base to lock the parts in place upon the rail.

The shoe as constructed in accordance with 50 the present invention comprises an elongated member having a slot formed longitudinally thereof to receive the rail edge, and this slot is formed with an upper inclined jaw 8 extending from one end of the shoe to the other and two lower jaws 9 and 10 disposed near the opposite ends of the shoe so as to provide an open space 55 11 between them. The slot has the vertical rear wall 12 and this rear wall, it should be noted, is disposed at an inclination to the longitudinal axis of the shoe and lies nearer the rounded outer wall of the shoe at its entrance end than at its tie 60 engaging end. The effect of this is to give the shoe a tapered or wedge action when supported in working position upon the rail, and to increase the depth of the slot at the entrance end of the shoe as will be apparent from Fig. 5.

65 The lower jaws 9 and 10 as shown lie in the same horizontal plane to engage the lower face 4 of the rail base and the upper jaw 8 at the tie engaging end of the shoe is given an inclination that corresponds closely with the slope of the upper face 6 of the rail base, and the distance 70 between the jaws 8 and 9 at this end of the shoe is just sufficient to embrace the upper and lower faces of the rail base when the shoe is applied thereto by hand, as will be apparent from Fig. 4.

75 An important feature of the present invention,

as above pointed out, resides in the construction whereby the jaws at one end of the shoe engage the rail base with a strong spring gripping action when the parts are in working position. This is secured in the embodiment of the invention 5 shown by making the distance between the outer portions of the upper and lower jaws 8 and 10 less than the thickness of the tapered portion of the rail base engaged therebetween, as will be apparent from Fig. 13, so that as the shoe is forced inwardly towards the rail edge 5 it will grip the rail base with a strong spring action that prevents displacement of the shoe longitudinally of the rail by the pressure of the shoe against the tie or while the yoke is being driven into locking 10 15 engagement with the shoe.

This gripping action at the entrance end of the shoe is preferably secured by forming the lower face of the jaw 8 so that its angle to the horizontal plane decreases towards the entrance 20 end of the shoe. In other words the upper sloping face 6 of a rail base usually lies at an angle of about 14 degrees to the lower face 4, and the present shoe for use upon a rail having this slope would be constructed so that the upper jaw 8 slopes at about 14 degrees at the abutment end and at about 11½ degrees at the shoe entrance end. This causes the shoe to engage the rail with a strong spring gripping action at its entrance end as the shoe is forced inwardly against 30 the rail edge, as will be apparent from Figs. 6, 7 and 8, and more particularly from Fig. 12 in which the inclination of the jaw 8 with respect to the dotted line a—a is readily seen. The line a—a is drawn parallel to the upper face of the 35 jaws 9, 10.

This shifting of the plane of the lower face of the jaw 8 from one end towards the other serves also to impart a slight canting action to the shoe forcing the jaw 9 at the tie engaging end of the 40 shoe upwardly into gripping action with the rail base in addition to the pinching of the rail base between the upper and lower jaws at the entering end of the shoe. In this manner a three 45 point gripping action upon the rail base is secured irrespective of slight variations that may occur in the thickness of the rail base.

The tie engaging end of the shoe is provided with the downwardly extending abutment 13 that is made relatively large so as to avoid damaging the tie 7 under heavy pressure, and the stiffness of the jaws 8 and 9 at this end of the shoe is increased by providing the abutment 13 with the jaw reenforcing flange 14. The strength of the abutment 13 is increased by providing it with the stiffening rib 15 extending 55 downwardly from the shoe along the abutment.

As a result of the stiffening effect of the flange 14 the jaws 8 and 9 are rigid and non-yielding at this end of the shoe while at the opposite end of the shoe they are sufficiently resilient to spring apart as they are forced into gripping engagement with the rail base.

The space 11 provided between the lower jaws 9 and 10 serves to reduce the weight of the shoe, but what is more important, it reduces the loosening effect of the vibration of the rail upon the shoe; that is, the traffic upon the rail produces vibration therein, but since the rail base is not engaged at its lower face between the jaws 9 and 10 it may vibrate between the jaws without disturbing the shoe.

Having described the construction of the shoe of the present invention, the yoke of the present 75

invention that cooperates therewith will now be described.

In the construction shown the yoke comprises a resilient shank or body portion 16 adapted to extend under and span the rail base 3. This shank is provided at one end with an upwardly extending hook 17 comprising a vertical wall 18 and a relatively short overhanging jaw 19 disposed at an angle corresponding to the slope of the upper face 6 of the rail base.

The shank 16 is so constructed that it engages the lower face 4 of the rail base only at the central portion of the rail and the remaining portions of the shank are disposed in spaced relation to the lower face of the rail, as shown. As a result of this construction the shank 16 engages the central portion of the rail base at 20 with a fulcrum action that holds the remaining portions of the shank in spaced yielding relation to the rail base, and this spring action of the shank 16 is utilized to hold the jaw 19 of the hook 17 in firm gripping engagement with the upper face 6 of the rail base.

The opposite end of the shank 16 is provided with a larger hook 21 adapted to embrace the shoe, and this portion of the shank is bent downwardly as shown in Fig. 2 to clear the lower face 22 of the shoe and adjacent portion of the rail base. The upper portion of the hook 21 comprises a jaw 23 that extends inwardly over a portion of the rail base, and this jaw in accordance with the present invention, is given a torsional twist in the direction of its length which causes the shoe engaging face 24 of the jaw to normally lie at an angle to a horizontal plane, as clearly shown in Fig. 10. This serves to facilitate the engagement of the yoke with the tapered end portion 25 of the shoe as shown in Fig. 11, and it also causes the jaw 23 to grip the upper face 26 of the shoe with a strong spring action, as will be apparent from Fig. 12 wherein the pressure of the inclined face 24 upon the shoe serves to twist the jaw from the dotted line position of this figure to the full line position and causes the face 24 to lie substantially parallel to the upper face 26 of the shoe.

The embracing engagement between the hook 21 and outer rounded portion 27 of the shoe is such that the yoke will be forced in the direction of its length to hold an edge of the wall 18 of the hook 17 against the rail edge 5 and at the same time hold the jaw 23 in firm clamping engagement with the upper face of the shoe.

This is accomplished in the present construction by forming the hook 21 of the yoke so that its inner curved wall that embraces the shoe is disposed eccentrically with respect to the central horizontal axis of the shoe and acts upon only that portion of the curved outer wall of the shoe which lies below the point X. This causes the jaw 23 to act upon the upper face 26 of the shoe with an increasing downward pressure as the yoke is driven upon the shoe, as will be apparent from Fig. 2 in which it will be seen that a clearance space is formed between the upper rounded portion of the shoe and hook from approximately the point indicated by X to the point where the jaw 23 engages the upper face of the shoe. The effect of this is to limit the torsional twist of the jaw 23 to the portion thereof above the point X and to force the yoke transversely of the rail so as to hold the short jaw 19 in firm gripping engagement with the rail base and exert a strong downward pressure upon the jaw 23 when the parts are in the working position.

The length of the yoke is such that the short hook 17 may be readily placed over the upper edge of the rail after the large hook 21 has been placed over the edge of the rail and moved laterally so that the inner curved portion of the hook 21 rests against the rail edge. That is the distance between the curved wall X of the hook 21 and inwardly extending end of the hook 19 is greater than the width of the rail base, to permit the ready application of the yoke to the rail by hand, while at the same time the yoke is sufficiently short to cause the desired clamping action to be exerted upon the parts as the yoke is driven upon the shoe.

Since the yoke does not at any time engage the portion of the shoe lying near the end flange 14 the size of the shoe may be reduced near this end as indicated at 28.

It will be seen from the foregoing that the rail anchor of the present invention may be readily applied to a rail as shown in Fig. 1 by placing the shoe by hand in the position in which it is shown in Fig. 4 whereupon the yoke is engaged with the rail by hand so that the hook 21 embraces the tapered end of the shoe as shown in Fig. 11. The operation is then completed by driving the yoke hook 21 along the inclined shoe until the desired clamping action is secured.

The spring action of the yoke and shoe jaws above described serves to maintain the parts in the working position and prevents the parts from working loose under the pressure of the shoe against the tie and rail vibration, and the clamping action upon the parts may be increased from time to time as desired by driving the yoke further upon the shoe. The parts may be removed from the rail when desired by driving the yoke in the reverse direction.

What is claimed is:

1. In a rail anchor, the combination of an elongated shoe having a slot extending longitudinally thereof to embrace an edge of a rail base and the slot being of less width at one end than the other so that the rail edge will freely enter the slot at one end while the other end of the slot grips the rail base with a strong spring action as the base is forced into the slot, and a yoke constructed to span the rail base and provided at one end with an upwardly extending portion adapted to engage one edge of the rail base and provided at its opposite end with a shoe embracing hook adapted to hold the shoe in gripping engagement with the rail base.

2. In a rail anchor, the combination of an elongated shoe having a slot extending longitudinally thereof to embrace an edge of a rail base and formed with a longitudinally extending upper jaw and non-continuous lower jaws one of which lies closer to the upper jaw than the other so that the rail edge will freely enter the slot at one end while the jaws at the other end of the slot grip the rail base with a strong spring action, and a yoke constructed to span the rail base and provided at one end with an upwardly extending portion adapted to engage one edge of the rail base and provided at its opposite end with a shoe embracing hook adapted to hold the shoe jaws in firm gripping engagement with the rail base.

3. In a rail anchor, the combination of an elongated shoe having a tie abutment flange at one end and a slot extending longitudinally of the shoe to embrace an edge of a rail base and the slot being shaped so that the rail edge will

- freely enter between the slot jaws at the flange end of the shoe while the distance between the inner surfaces of the outer portions of the slot jaws at the other end of the shoe is less than the thickness of the rail flange to be introduced therebetween so that these jaws grip the rail flange with a strong spring action as the rail base flange is forced into the slot, and a yoke constructed to span the rail base and engage one edge thereof and provided at its opposite end with a shoe embracing hook adapted to hold the shoe slot in firm gripping engagement with the rail base.
4. In a rail anchor, the combination of an elongated shoe having a slot extending longitudinally thereof to embrace an edge of a rail base and provided with two non-continuous lower jaws and an upper jaw that slopes downwardly at its outer edge from one end to the other towards the plane of the lower jaws to reduce the width of the slot at one end so that the rail edge will freely enter the slot at one end while the jaws at the other end grip the rail base with a strong spring action and cant the shoe sufficiently to hold the second lower jaw firmly against the rail base, and a yoke constructed to span the rail base and engage one edge thereof and provided at its opposite end with a shoe embracing hook adapted to hold the shoe jaws in firm gripping engagement with the rail base.
5. In a rail anchor, the combination of an elongated shoe provided with a depending tie abutment and jaws adapted to embrace the outer

portion of the rail base flange, the jaws being so positioned as to provide a free hand fit on the rail in the region of the abutment end and arranged so that they are heavily reenforced at this end by the tie abutment and are practically rigid, and disposed closer together at the opposite end of the shoe where the jaws are more flexible to provide a driving fit that exerts a strong spring gripping action upon the rail base at this end, and a yoke adapted to span the rail base and provided with upwardly extending end portions one of which is adapted to engage an edge portion of the rail base and the other is adapted to embrace the shoe and hold its jaws in firm gripping engagement with the rail base.

6. In a rail anchor, the combination of a metal shoe constructed with a longitudinal slot of less width at one end than the other so that the rail edge will freely enter the slot at one end while the other end of the slot grips the rail base with a strong spring action as the base is forced into the slot, and a yoke constructed to span the rail base and provided with a hook to engage one edge of the rail base and a relatively larger hook at the other end which is given an initial twist about its longitudinal axis to engage the metal shoe and impart to the hook a strong spring action against the shoe by slight distortion of the initial twist of the hook as the parts are moved into cooperative relation.

CHARLES G. ERICSON.
